(75) Inventor: **Lars Johansson**, Jonstrop (SE)

Primary Examiner—Lisa Lichtenstein

(73) Assignee: **AB PH. Nederman & Co.**,
Helsingborg (SE)

(74) Attorney, Agent, or Firm—Tarolli, Sundheim, Covell,
Tummino & Szabo L.L.P.

(**) Term: **14 Years**

(57) **CLAIM**

(21) Appl. No.: **29/141,637**

The ornamental design for a extraction device for polluted
gases, as shown and described.

(22) Filed: **May 10, 2001**

DESCRIPTION

(30) **Foreign Application Priority Data**

Nov. 30, 2000 (SE) 00-2201

FIG. 1 is a perspective view of the extraction device;
FIG. 2 is another perspective view of the extraction device;
FIG. 3 is a side elevational view of the extraction device;
FIG. 4 is a side elevational view of the opposite side of the
extraction device;
FIG. 5 is a front elevational view of the extraction device;
FIG. 6 is a rear elevational view of the extraction device;
FIG. 7 is a top plan view of the extraction device; and,
FIG. 8 is a bottom plan view of the extraction device.
